FISH LURE

Edward N. Kellogg, Harrisville, Mich.

Application December 15, 1958, Serial No. 53,767

Term of patent 14 years

(Cl. D31—4)

Fig. 1 is a side elevational view of a fish lure embodying my design.

Fig. 2 is a top plan view thereof.

Fig. 3 is a bottom plan view thereof.

Fig. 4 is a left end view thereof.

Fig. 5 is a right end view thereof.

I claim:

The ornamental design for a fish lure, as shown.
